United States Patent Office

Des. 188,936
Patented Oct. 4, 1960

188,936

DATA INTEGRATOR CONSOLE OR SIMILAR ARTICLE

Albert Hohmann, Brooklyn, N.Y., assignor to American
Electronics, Inc., Los Angeles, Calif., a corporation
of California

Filed Nov. 9, 1959, Ser. No. 58,286

Term of patent 14 years

(Cl. D26—5)

FIG. I.

FIG. 3.

FIG. 2.

Figure 1 is a front perspective view of a data integrator console or similar article, showing my new design;

Figure 2 is a side elevational view, the opposite side being substantially a mirror image thereof; and

Figure 3 is a rear elevational view thereof.

The legible matter shown in broken lines is for illustrative purposes only.

I claim:

The ornamental design for a data integrator console or similar article, substantially as shown and described.
